UNITED STATES PATENT OFFICE.

WILLIAM L. MARDEN, OF ELMHURST, NEW YORK, ASSIGNOR TO NEPTUNE METER COMPANY, OF NEW YORK, N. Y., A CORPORATION OF NEW JERSEY.

ALARM REGISTER FOR METERS.

Application filed May 4, 1926. Serial No. 106,779.

The object of this invention is to provide for meter registers which must be capable of being set back to zero after operation, an alarm which shall be sounded on the delivery 5 of a predetermined volume of liquid as in the case of gasoline filling stations.

The invention will be explained more fully hereinafter with reference to the accompanying drawing in which it is illustrated and in 10 which:

Figure 1 is a view in elevation, as seen from the right-hand in Figure 2, of so much of a register, with its associated devices, as is necessary to enable the application of the 15 invention thereto to be understood.

Figure 2 is a view of the same in sectional elevation, as seen from the left-hand in Figure 1.

In the embodiment of the invention illustrated in the drawing, the registering mechanism, indicated generally at *a*, is enclosed within a suitable casing *b* which supports a suitable dial *c*. The register casing is intended to be supported upon a meter of suitable construction from which the registering mechanism receives motion through a vertical shaft *d*. In the construction shown, the shaft *d*, through gears *d'* and *d''*, drives a shaft *d''* which carries a unit indicator hand 20 *d''*. The shaft *d*, in the construction shown, also carries a gear *d''* which meshes with a pinion *e* on a drive shaft *e'* which is mounted in suitable bearings in the supporting framework and carries a worm *e''* for the operation of a totalizing register of usual construction, indicated by broken lines at *f'*.

The shaft *e'* also carries a worm *e''* which drives, through suitable transmission gearing, not necessary to be shown herein, a 25 shaft *h* which carries, usually through a sleeve *h''*, an indicating hand or pointer *h''* and has, in front of the protecting glass *c'*, a handle *h''* by which the pointer *h''* can be set back to zero, after an operation, and with it the shaft *h*.

On the shaft *h* is secured a cam *i* for cooperation with a hammer or striker *k*, pivoted at *k'*, formed with a lip *k''* which overhangs the framework for the purpose of 30 limiting the movement of the body of the hammer, and carries, on a spring arm *k''*, a

hammer head *k''*, for cooperation with a gong *k''*. On the body *k'* of the hammer is pivotally mounted a dog *k''*, which is arranged to rest on the cam *i* and, while swinging freely 55 in a counter-clockwise direction, is prevented from movement in the opposite direction by a suitable stop *k''*.

It will now be understood that in the operation of the registering devices the cam *i*, 60 rotating in the direction of the arrow from its initial or zero position, through contact with the dog *k''*, raises the hammer *k'* until, in the continued operation of the registering mechanism, the high point of the cam passes 65 beyond the dog *k''*, whereupon the hammer falls and the head *k''*, by reason of the spring arm *k''*, strikes the gong *k''* and gives the audible signal required. Through the provision of the pivoted dog *k''*, which is free 70 to swing in a counter-clockwise direction, the resetting of the indicator *k''*, which is affected by rotation of the shaft *h* and the cam *i* in a clockwise direction, as seen from the rear, in Figure 1, is permitted, the dog *k''* swinging freely as it is struck by the drop of the cam.

It will be understood that the invention is in no wise dependent upon the construction of the registering mechanism except so far 80 as it involves the reverse rotation of the shaft *h* and cam *i* in the operation of resetting.

I claim as my invention:

In a meter register having a driving 85 means, an indicator, a shaft carrying the indicator, and means to reset the shaft by reverse rotation, a cam with a sharp drop carried by the shaft, a gong, a pivoted hammer, a dog freely movable in one direction pivoted on the hammer and operated by the cam, and a stop on the hammer to prevent movement of the dog in the opposite direction, whereby reverse rotation of the cam causes the dog to move away from the stop 90 while maintaining the alarm mechanism in operative condition during normal operation of the register.

This specification signed this 29 day of April A. D. 1926.

WILLIAM L. MARDEN.
